United States Patent Office

Des. 203,225
Patented Dec. 14, 1965

203,225

JUG

Martin Schnur, 220 St. Cloud Ave., West Orange, N.J.,
and Mel Appel, 9 Nottingham Road, Livingston, N.J.

Filed Dec. 18, 1964, Ser. No. 83,077

Term of patent 14 years

(Cl. D58—5)

FIG. 1 is a side elevational view of a jug, showing our new design;

FIG. 2 is an elevational view thereof taken from the right of FIG. 1;

FIG. 3 is an elevational view thereof taken from the left of FIG. 1; and

FIG. 4 is a top plan view thereof.

The dominant features of our design reside in the portions shown in full lines.

We claim:

The ornamental design for a jug, as shown and described.
